(57) **CLAIM**

The ornamental design for an occupancy sensor fascia cover plate, as shown and described.

DESCRIPTION

FIG. 1 is a perspective view of the top, front, and left side of the occupancy sensor fascia cover plate mounted on a housing shown in phantom illustrating the new and ornamental design;

FIG. 2 is a rear elevational view of the occupancy sensor fascia cover plate shown in phantom lines.

FIG. 3 is a top plan view of the fascia cover plate illustrated in FIGS. 1-2;

FIG. 4 is a right side elevational view of the fascia cover plate illustrated in FIGS. 1-3, the left side being a mirror image thereof;

FIG. 5 is a front elevational view of the fascia cover plate illustrated in FIGS. 1-4; and,

FIG. 6 is a bottom plan view of the fascia cover plate illustrated in FIGS. 1-5.

The phantom lines are shown for illustrative purposes only and form no part of the claimed design.
